[57]

CLAIM

The ornamental design for a panel for playground structure, as shown and described.

DESCRIPTION

FIG. 1 is an enlarged top right front perspective view of a panel for playground structure showing my new design; FIG. 2 is a top plan view thereof;

FIG. 3 is a front elevational view thereof;

FIG. 4 is a bottom plan view thereof;

FIG. 5 is a right side elevational view thereof;

FIG. 6 is a rear elevational view thereof;

FIG. 7 is a left side elevational view thereof;

FIG. 8 is an enlarged top right front perspective view of an alternate embodiment of a panel for playground structure showing my new design;

FIG. 9 is a front elevational view of the alternate embodiment;

FIG. 10 is a rear elevational view of the alternate embodiment;

FIG. 11 is a top plan view of the alternate embodiment; the undisclosed bottom plan view is identical to FIG. 4;

FIG. 12 is a right side elevational view of the alternate embodiment; and,

FIG. 13 is a left side elevational view of the alternate embodiment.
